UNITED STATES PATENT OFFICE.

ALBERT H. SIMMONS, OF WHEATON, ILLINOIS, ASSIGNOR TO EDISON ELECTRIC APPLIANCE COMPANY, INC., OF CHICAGO, ILLINOIS, A CORPORATION OF NEW YORK.

DESIGN FOR SUGAR BOWL OR SIMILAR ARTICLE.

Application filed May 18, 1926. Serial No. 17,767. Term of patent 14 years.

To all whom it may concern:

Be it known that I, ALBERT H. SIMMONS, a citizen of the United States, residing at Wheaton, in the county of Du Page and State of Illinois, have invented a new, original, and ornamental Design for Sugar Bowls or Similar Articles, of which the following is a specification, reference being had to the accompanying drawing, forming a part thereof.

The single figure of the drawing is a side view of a sugar bowl embodying my new design.

I claim:

The ornamental design for sugar bowl or similar article, substantially as shown.

In witness whereof, I have hereunto set my hand this 12th day of May, 1926.

ALBERT H. SIMMONS.
